UNITED STATES PATENT OFFICE

2,382,795

LOOM HARNESS

John Jacob Kaufmann, Elkins Park, Pa., assignor
to Steel Heddle Manufacturing Company,
Philadelphia, Pa., a corporation of Pennsyl-
vania

Application January 21, 1944, Serial No. 519,102

5 Claims. (Cl. 139—96)

This invention relates to the loom harness, and it relates more particularly to the construction and arrangement of the heddles used in such harness for the purpose of separating the warp threads to form successive sheds through which the shuttle is passed to effect the weaving operation.

The invention relates more particularly to that type of heddles for loom harness which are made from thin flat metal strips, and which are now almost universally used for weaving textile fabrics.

The principal object of the present invention is to provide heddles made of thin flat strips of metal, such as steel, of such construction and arrangement that the same will have a certain desired degree of resiliency in a vertical or longitudinal direction, whereby there will be an easing of the shock when reversals of movement of the harness frames takes place during the shedding operations.

A further object of the invention is to provide heddles of the character aforesaid in which the heddles will be flexible longitudinally whereby there will be less tendency to break such of the warp threads as are tighter than the main body of the warp.

It is understood that heretofore attempts have been made in various ways to provide heddles having a certain amount of flexibility, but none of the structures or devices for this purpose heretofore suggested have proved to be practical, and particularly the same are not adaptable for use in connection with the high speed looms at present in common use.

With the foregoing objects in view, the invention contemplates the provision of heddles made of thin flat metal, provided at their central portions with the usual warp controlling eyes, at their ends with mortises for mounting the same on the heddle rods of the frames, and provided with means above or below the shed lines for imparting flexibility longitudinally to the individual heddles, said means comprising the bending of a portion of the metal out of the main plane of the body portion of the heddle, reducing the cross-sectional area of the bent out portions, and providing the heddles, if desired, with spacing devices either for use in connection with drawing-in machines or to insure freedom of movement of the warp when the shedding takes place.

The nature and characteristic features of the invention will be more readily understood from the following description taken in connection

with the accompanying drawings, forming part hereof, in which:

Fig. 1 is a front elevation of a group of heddles embodying the main features of the present invention, portions of the heddle rods on which they are mounted also being shown;

Fig. 2 is a side elevation thereof, the heddle rods being shown in section;

Fig. 3 is a view similar to Fig. 2, but illustrating a modified form of heddle;

Figs. 4 and 5 are views similar to Figs. 1 and 2, respectively, illustrating another modified form;

Figs. 6 and 7 are views similar to Figs. 1 and 2, respectively, illustrating another modified form;

Figs. 8 and 9 are views similar to Figs. 1 and 2, respectively, illustrating another modified form; and

Figs. 10 and 11 are views similar to Figs. 1 and 2, respectively, illustrating another modified form.

Referring now more particularly to Figs. 1 and 2 of the drawings, the heddles 20 there shown are in the main of a common and well known type, commonly used in the weaving of textile fabrics, the same preferably being made of thin flat strips of steel wire each provided at its respective central portion with the usual warp controlling eye 21. At each end of each heddle 20 there is also provided a mortise 22 for mounting the heddles on the heddle rods 23 which are suitably supported in the heddle frames (not shown). The method of formation of the warp eyes 21 and mortises 22 is preferably that which is well known and commonly practiced in the industry.

In the form of the invention shown in Figs. 1 and 2 of the drawings there is provided, adjacent the upper heddle supporting rod 23, on each heddle 20, a portion 24, bent in reverse curvature in a form or shape somewhat similar to an elongated S, parts of which are definitely disposed outside the plane of the main or body portion of the heddle 20. At the place where the bent out portion 24 is provided, the heddle 20 may be left the full width of the strip as shown in Fig. 3, but preferably the same is cut away at the sides, as at 25, thereby to provide a reduced area of cross-section in the bent portion, and thus providing greater flexibility when strain is imparted to the heddle in a longitudinal direction.

In the form of the invention shown in Figs. 4 and 5 of the drawings each of the heddles 20 is provided with bent out portions 24 at both the top and bottom, in each instance, however, being located at a point where the same is disposed beyond the plane of the sheet of warp when the

shed is formed. Also in this form the reduction in the cross-sectional area of the bent out portions 24 is effected by slotting the strip at this point as at 26.

In the form of the invention shown in Figs. 6 and 7 of the drawings the bent out portion 24a is in the shape of a flattened V. Here again, however, the reduction in the cross-sectional area is obtained by slotting the strip as at 26 at the point where the bent out portion 24a is provided.

In Figs. 8 and 9 of the drawings there is shown another form of the invention somewhat similar to that shown in Figs. 6 and 7. In this case, however, the bent out portions 24a are provided at both the top and bottom of the heddles 20, in each instance, however, being beyond the plane of the sheet of warp when the shed is formed.

In Figs. 10 and 11 of the drawings there is shown still another modified form of the invention in which the heddle 20 is bent at the desired location, as at 24b, out of the plane of the main body portion of the heddle 20, continuing in a straight inclined direction for the desired distance, and then being bent back to cause the end portions to be disposed parallel to that of the plane of the main body portion. Here again there is provided a reduction in cross-sectional area at the bent portion by slotting the strip as at 26, and the bends are provided preferably at the top and bottom of each heddle.

If desired, any of the various forms may be provided with suitable spacing projections 27 which may be formed, for example, as described and shown in my previous Letters Patent No. 1,970,175, which will serve not only to assist in the manipulation of the heddle when the entering is done by means of a warp drawing-in machine, but will also insure greater freedom of movement of the warp as the shedding takes place in the operation of the loom.

It will of course be apparent that the bent out portion of the heddles in a particular frame will be disposed at the same longitudinal locations, so that said bent out portions will readily nest with respect to each other.

By the construction and arrangement in accordance with the present invention, there is provided an improved type of heddle which will not only serve to relieve the strain when the shed is formed, but will also operate effectively to relieve the shocks caused by the inertia of the heddle masses when the reversal of movement takes place as the heddle frames are raised and lowered in the operation of the loom. Heddles of this type will also serve to relieve individually the tension of unduly tight warp ends, and thus minimize breakage of the same and the consequent stoppages of the loom for the purpose of tying up broken ends.

I claim:

1. In a loom harness, a plurality of heddles for controlling the warp ends, rods for supporting said heddles, each of said heddles being made of a thin flat metal strip having a central warp eye and having mortises at each end for mounting said heddles on said rods, each of said heddles also having a straight portion extending above and below the central warp eye to a point beyond the shed line, and having portions bent out of

the plane of the main body portion of the heddle to provide longitudinal flexibility, said bent out portions being disposed between said straight portions and the end mortises and being cut away to provide a reduced cross-section of said bent out portions.

2. In a loom harness, a plurality of heddles for controlling the warp ends, rods for supporting said heddles, each of said heddles being made of a thin flat metal strip having a central warp eye and having mortises at each end for mounting said heddles on said rods, each of said heddles also having a straight portion extending above and below the central warp eye to a point beyond the shed line and having portions bent out of the plane of the main body portion of the heddle to provide longitudinal flexibility, said bent out portions being disposed between said straight portions and the end mortises, and certain of the heddles having spacing projections adjacent said bent out portions.

3. In a loom harness, a plurality of heddles for controlling the warp ends, rods for supporting said heddles, each of said heddles being made of a thin flat metal strip having a central warp eye and having mortises at each end for mounting said heddles on said rods, each of said heddles also having a straight portion extending above and below the central warp eye to a point beyond the shed line and having portions bent out of the plane of the main body portion of the heddle to provide longitudinal flexibility, said bent out portions being disposed between said straight portions and the end mortises and being cut away to provide a reduced cross-section of said bent out portions, and certain of the heddles having spacing projections adjacent said bent out portions.

4. In a loom harness, a plurality of heddles for controlling the warp ends, rods for supporting said heddles, each of said heddles being made of a thin flat metal strip having a central warp eye and having mortises at each end for mounting said heddles on said rods, each of said heddles also having a straight portion extending above and below the central warp eye to a point beyond the shed line and having portions bent out of the plane of the main body portion of the heddle to provide longitudinal flexibility, said bent out portions being disposed between said straight portions and the end mortises and being slotted to provide a reduced cross-section of said bent out portions.

5. In a loom harness, a plurality of heddles for controlling the warp ends, rods for supporting said heddles, each of said heddles being made of a thin flat metal strip having a central warp eye and having mortises at each end for mounting said heddles on said rods, each of said heddles also having a straight portion extending above and below the central warp eye and having portions bent out of the plane of the main body portion of the heddle to provide longitudinal flexibility, said bent out portions being disposed between said straight portions and the end mortises and being cut away to provide a reduced cross-section of said bent out portions.

JOHN JACOB KAUFMANN.
